UNITED STATES PATENT OFFICE.

HENRY C. STABY, OF BROOKLYN, NEW YORK.

DESIGN FOR A MAP-CASING.

No. 40,232.

Specification for Design.

Patented Aug. 17, 1909.

Application filed June 18, 1909. Serial No. 503,038. Term of patent 7 years.

To all whom it may concern:

Be it known that I, HENRY C. STABY, a citizen of the United States, residing at Brooklyn, in the county of Kings and State of New York, have invented a new, original, and ornamental Design for a Map-Casing, of which the following is a specification, reference being had to the accompanying drawings, forming a part thereof, and in which—

Figure 1 is a front elevation, Fig. 2 a top view, and Fig. 3 an end view of a map casing embodying my design.

The leading features of my design pertain to the ornamental form and configuration of the casing as a whole.

I claim:

The ornamental design for a map casing, as shown.

HENRY C. STABY.
